UNITED STATES PATENT OFFICE.

FRED I. GETTY, OF JENNINGS, LOUISIANA.

PUMP.

1,036,094.

Specification of Letters Patent. Patented Aug. 20, 1912.

Application filed November 4, 1910. Serial No. 590,698.

To all whom it may concern:

Be it known that I, FRED I. GETTY, a citizen of the United States, residing at Jennings, in the parish of Calcasieu and State of Louisiana, have invented certain new and useful Improvements in Pumps, of which the following is a specification.

This invention relates to improvements in centrifugal pumps, and more particularly 10 to those generally known as deep well pumps.

The object of the invention is to provide a pump of the class stated which is adapted to efficiently deliver water, in large or small 15 volume, and capable of operating in a comparatively small space, and with a comparatively small expenditure of power for propelling it.

A further object of this invention is to 20 provide a pump, which is adapted to operate, and which can be conveniently installed at any desired depth, and which operates equally well whether the water level in the ground be high or low.

25 The invention also aims to provide a centrifugal pump construction which so impels and guides the water, that it continues in the same general direction given it by the impeller, along curved lines of large diameter, thereby greatly reducing to a minimum 30 the frictional resistance incurred by the water in its passage through the pit.

The invention also comprehends improvements in the specific details of construction 35 and arrangements of parts, which will be hereinafter and more fully pointed out in the claims.

40 In the drawings: Figure 1 is a view partially in section, and partially in elevation of the upper portion of my improved pump. Fig. 2 is a view similar to Fig. 1, but illustrating the lower portion of the pump structure. Fig. 3 is a vertical section on the line 3—3 of Fig. 4, illustrating on an enlarged 45 scale the pump structure. Fig. 4 is a horizontal section on the line 4—4, Fig. 3. Fig. 5 is a detail view partly in section of the pump head. Fig. 6 is a detail horizontal section of the same on the line 6—6, Fig. 5. 50 The same numerals refer to like parts in all the figures.

1 indicates a tube, composed of as many

sections as may be found desirable, the sections being coupled together by the usual 55 couplings, 2. Near the bottom of the tube 1, is a strainer 3, of any approved pattern. The upper end of the tube is threaded, to engage a threaded hollow cap 4, the upper portion of which is reduced, and is provided on its outer surface with two beveled 60 spaced apart cam lugs 5, and below the same is a beveled flange 6. The cap supports the pit 7, the latter comprising a base 8, receiving chamber 9, and a dome 16. The base is provided with a neck, the lower edge of 65 which is beveled as at 11^a to coöperate with the beveled flange 6, and is further provided with internal spaced apart cam lugs 11, which coöperate with the spaced lugs 5. The cam lugs 5 and 11, form a means for 70 locking the pit to the cap, the cam surfaces causing the two beveled edges 6 and 11^a to tightly impinge to form a water tight joint between the parts when assembled.

The base flares upwardly from the neck, 75 and then extends in a vertical plane, to form a surface to which the lower end of the body portion 9 of the pit is bolted, as indicated at 13. The upper inner surface of the vertical portion of the base inclines upwardly 80 from the inner edge, and is concave as shown at 14, for a purpose to be described.

The walls of the body portion 9 of the pit are vertical above the concave surface of the base to form an uninterrupted passage for the water when introduced to the pit by the impeller, and is somewhat reduced in diameter above the impeller. At the upper end of the reduced portion is a ring 15, to which is bolted a dome 16, the upper 90 end being flanged and formed with an opening 17, and below the flange is an outlet opening 18, in which fits a discharge pipe 18^a. The discharge pipe inclines upwardly which permits of the pump being set low, 95 to accommodate belting, and to deliver to an elevated flume. A pump head 10 fits in the opening 17, and has a flange 19, which is bolted to the flange of the dome. The head extends down within the dome, and upwardly above the latter as shown in Fig. 1. An opening 20 extends entirely through the head to accommodate an impeller shaft. The head is formed with a water receiving

- chamber 21, which communicates with the dome by means of an opening 22. An overflow pipe 23 extends upwardly within the water chamber, and it communicates with an outlet pipe 24, tapped in the flange 19. Above the water chamber 20, is an oil chamber 25, supplied with lubricating oil by means of a pipe 26, connected to an oil cup 27.
- 10 Secured to the lower end of the pump head 10, is the split end of a tubular section 30, of a column 31, which supports the operating parts of the pump. The section is clamped to the head by means of a bolt 32, and its lower end is threaded to receive a coupling 33, by means of which another section 34 is attached. The column is made up of these sections, the lower one 35, terminating in a cap plate 36. The cap plate is bolted to a ring 37, having a plurality of grooves 38, formed on its under side to receive a series of spaced vertical tangentially arranged curved vanes, 39. The lower edges of the vanes fit in grooves 40, formed in the upper edge of a cup shape bottom member 41. The member 41, is reduced at its lower end to fit within the hollow cap 4, and is internally threaded to receive a short section of pipe 42. Just above and outside of the lower reduced end of the cup member 41, is a groove 43, to receive packing rings 44, against which the upper end of the hollow cap abuts to form a water tight joint.
- 15 The upper and lower ends of the vertically disposed curved vanes are riveted as indicated at 45, to the ring 37, and the cup shape member 41, respectively. By this construction, the ring vanes, and cup member, form a cage, to receive the impeller as clearly shown in Fig. 3.
- 20 The impeller shaft 46, is mounted in the pump head 10, and the tubular column 31, and extends below the same, and has attached thereto a disk 47, from the under side of the center of which depends a cone 48. Secured to the under side of the disk 47 is a series of impellers 49. Each impeller is pointed at its ends, and is curved to throw the water outwardly toward the curved
- 25 vanes. The inner ends of the impellers terminate at the outer edge of the cone 48, while the outer ends terminate at the edge of the disk 47 and in proximity to the vanes. The impellers are arranged with relation to each other so that the intake space formed between them is narrower than the outlet at the circumference of the disk 47 whereby the water is prevented from choking.
- 30 To the underside of the impellers is fastened a disk 50, formed with a centrally disposed, depending, tubular, hollow extension 51. The extension 51 is in alinement with the opening 41^a, in the cup shape member 41, and its edge is normally slightly spaced from the upper surface of the latter, as indicated at 52, to permit of a slight adjustment of the impeller that it may be properly positioned with reference to the vanes.
- 35 The tubular column 31 is provided at suitable intervals with bearings 53, for the shaft 46, and in order to brace the column as much as possible and to fill the space between the shaft and the casing the spaces between these bearings and the column are provided with wooden filling blocks 54. These blocks serve to stiffen the column, and at the same time assist in retaining the shaft in alinement. The opening in the lowermost section of the vertical column 31 is reduced and a bushing 56, is placed therein to form a substantial bearing for the shaft just above the impeller.
- 40 There are three collars placed on the shaft 46 in the oil well 25, the lower one 57 being supported on a bushing 58, mounted in the pump head 10. The intermediate ring 59, is formed with a plurality of openings 60, for the reception of balls 61, which have a bearing on the lower ring while the upper ring 62, engages the upper surface of said balls. A pulley 63, is secured to the upper end of the shaft 46 and its hub is supported on the upper ring 62. The pulley is hollow and fits over the pump head as shown in Fig. 1.
- 45 In operation, the tube and the pit are sunk into the ground to a depth sufficient to insure a supply of water, and the parts are assembled, as described. When power is applied to the pulley 63, the impeller is revolved within its surrounding cage and throws the water out by centrifugal force against the concave surface 14, and the vertical walls of the receiving chamber 9. When the water is driven out by the impeller it passes through the spaces formed between the vanes at a high rate of speed, striking the concave surface of the pit at a very oblique angle, then continuing, without change of direction, on a spiral course upward. In its upward spiral course the speed of the water is gradually reduced, and is transformed into pressure.
- 50 From practical experiments I find that the pressure of the water resulting from the relative location of the vanes with reference to the impeller, cannot be successfully utilized to the best advantage, unless the walls of the pit are so arranged to permit of the column of water to continue to flow upward in a spiral course, in an uninterrupted passage. To meet this contingency the inner surface of the pit is vertical adjacent the vanes, and furthermore the upper inclined surface of the base 8 is concave. As the water is forced out through the spaces between the vanes it contacts with the concave surface 14 and the vertical wall of the pit and is thereby spirally lifted in a solid column in the pit. This spiral action of the water in the pit relieves the pressure on the water in

the cage, and thereby does not retard the lifting action of the impeller. Of course, after the column of water is elevated some distance in the pit, the spiral action is gradually decreased and the water rises by the pressure below until the outlet opening is reached.

It will be observed that the passages between the vanes are so arranged that the currents of water are unobstructed and therefore follow their natural course. That is to say the walls of the passages do not change the direction nor impede the velocity of the natural flow of the water when thrown out from the center of the pump, but allows same to flow in unimpeded tangential streams out of the cage and into the casing.

I find that by constructing the impeller and the vanes and pit surfaces in the manner set forth, that the water is effectually lifted whether the well be deep or shallow. I also find that an increase in the speed of the impeller is followed by an increase in the volume of water pumped, which is a decided advantage. The disposition of the vanes, with relation to the pit allows the free passage of the water, and prevents its return to the periphery of the impeller.

The impeller is wholly supported at the upper end of the pit, so as to permit of a variety of adjustment in the cage with reference to the vanes, whereby to secure the best possible results.

The bearing in the pump head receives considerable friction, due to the fact that the impeller is supported thereby. Therefore, I find it quite essential that provision be made for cooling the bearing, and it is for this reason I arrange the water jacket. As the water rises in the pit, a small supply will pass up through the openings 22, and into the chamber 21, and overflow through the pipe 23. This constant circulation of the water keeps the head and the bearing sufficiently cool to prevent destruction of the parts by friction.

By elevating the discharge end of the pipe 18°, it assists in starting the water to circulate in the bearing in the pump head. If an elevated discharge pipe is not employed, the water may be started through the chamber by temporarily covering the end of the pipe, which causes it to back up, and after the cover is removed and the water enters the chamber it will continue to flow as long as the pump runs, as the escape pipe 24, acts as a siphon.

Having thus described my invention what I claim is:

1. In a pump, the combination of a cylindrical pit having an exit opening near its top, a plurality of spaced apart stationary vanes supported in the cylindrical pit and spaced from the walls thereof, each of said

vanes being tangential on its two surfaces from end to end, the space between the wall of the pit and the outer end of the vanes forming an annular unobstructed passage around the outside of said vanes which communicates with the outlet opening, a revolving impeller mounted within the vanes and having curved blades arranged tangentially to its axis, the outer end portion of the curved blades terminating and revolving on the concentric line formed by the inner ends of the tangential vanes and in close proximity thereto, whereby the water is forced by the impeller through the spaces between the vanes in the direction of the motion of the blades in uninterrupted tangential streams into the annular space, the uninterrupted streams of water contacting with the cylindrical wall of the pit, imparting to the volume of water, a rotary and spiral motion, as it travels upward from the pump, means for suspending the impeller and revolving the same.

2. In a pump, the combination with a pit, the lower wall of which is vertical, a base to which the pit is secured, the upper edge of the base being upwardly inclined and concave, a series of locking cams on the base, a tube having on its upper end a series of locking lugs which coöperate with the locking lugs on the base, the tube also having a beveled flange on which the lower end of the base fits when the locking lugs are engaged, a cage supported on the upper end of the tube and including spaced apart vanes, said vanes being spaced from the vertical wall of the pit, an impeller mounted in the cage, and a shaft attached to the impeller.

3. In a pump of the class described, the combination of a pit, a head on the pit, a shaft suspended from the head, an impeller on the lower end of the shaft, a casing formed in sections and spaced from and surrounding the shaft, fastening means securing the casing to the head, spaced apart bearings in the casing below the fastening means to form a support for the shaft, and lagging fitting snugly in the spaces formed between the bearings and the shaft and the casing whereby to add rigidity throughout the length of the casing.

4. In a pump, the combination of a tube, a cup shape member having a central opening and a groove to fit over the tube, packing in the groove, said cup shape member having a series of grooves in its upper edge, a series of vanes mounted in the grooves in the edge of the cup shape member, means for securing the lower ends of the vanes to the cup shape member, a frame having a series of grooves on its lower edge to receive the upper edges of the vanes, means for securing the upper ends of the vanes to the frame, an impeller operating within the plane of the vanes, and a pit surrounding

- the vanes, and spaced therefrom, the wall of the pit being uninterrupted adjacent the vanes whereby the water forced through the spaces between the vanes will rise in a spiral column.
5. In a pump, the combination with a cylindrical pit, a head on the pit, a cage supported in the pit and including a series of spaced apart vanes, said vanes being tangent from end to end in one direction and spaced from the wall of the cylindrical pit, to form an annular unobstructed passage, an impeller mounted in the cage, a tubular casing extending up from the cage, a shaft 70 mounted in the casing and secured to the impeller, means for securing the casing to the head, bearings in the casing to support the shaft, and lagging within the casing and surrounding the shaft between the bearings, 75 15 and means for suspending the shaft from the head.
6. In a pump, the combination of a pit, a cage including a series of spaced apart vanes, an impeller mounted in the cage, a shaft secured to the impeller, a plate attached to the impeller and formed with a central depending flange formed with an opening, said flange registering with an opening formed in the bottom of the cage, a 80 vertical tube at the bottom of the cage, and means for locking the tube to the cage, said tube being located in alignment with the flange.
7. In a pump, the combination with a pit, 85 a head on the pit, a shaft suspended on the head, a tubular column secured to the head, a cage supported on the tubular column and including a series of vanes, an impeller within the cage and secured to the shaft, the bottom of the cage having a depending tubular extension, and a groove, a tube extending below the pit, and a detachable coupling between the bottom of the pit and the last mentioned tube, the upper end of the coupling fitting in the groove and against the packing.
8. In a pump of the class described, the combination of a pit, a head on the upper end of the pit, said head having a depending sleeve, a shaft mounted in the head and depending in the pit, an impeller mounted on the end of the shaft, a tubular casing secured to the depending sleeve and surrounding the shaft, a bearing in the bottom of the 90 95 casing for the shaft, bearings fitting in the casing at intervals between the lower bearing and the depending sleeve, and lagging in the casing surrounding the shaft to fill the space between the bearings.
9. In a pump of the character described, the combination of a pit, a head on the upper end of the pit, said head having a depending sleeve, a sectional shaft supported in the head, a sectional casing secured on the depending sleeve and formed near its 100 105 110 115 120 125 130 bottom with a bearing, bearings fitting in the casing between the lower bearing therein and the head of the sectional shaft fitting in said bearings, and lagging filling the space between the shaft and casing and between the bearings.
10. In a pump of the class described, the combination of a cylindrical pit, a head mounted on the top of the pit, a shaft supported on the head, an impeller formed with an opening in its bottom and mounted on the lower end of the shaft, the blades of the impeller being tangent to the axis of said impeller, a casing surrounding the shaft and secured to the head, a cage having a series of spaced apart tangentially arranged vanes secured therein, the spaces between the vanes being uninterrupted and extending from end to end in one direction, the outer ends of the vanes being spaced from the cylindrical wall of the pit to provide an annular passage and means for supporting the said cage.
11. In a pump, the combination with a pit having a base, of a tube, locking means between the base and tube, a pump located within said pit and surrounded by an annular series of unobstructed passages spaced from the walls of the pit, said pump being supported on the tube, packing interposed between the said tube and pump, said latter space entirely surrounding the pump, a shaft connected to said pump, and a casing inclosing said shaft, whereby the pump will discharge water into the space and against the walls of the pit in a series of streams which impart an upward and rotary spiral motion to the column of water, and means for rotating said shaft and actuating the pump.
12. In a pump of the character described, the combination of a pit, a base to which the pit is secured, a head on the pit, a tube at the bottom of the base, a locking device between the base and the tube, a casing in the pit, the lower end of which is supported on the upper end of said tube, packing interposed between the pump and tube, a pump including impeller blades and a shaft mounted in the casing, the pump being spaced from the walls of the pit to form an annular unobstructed passage above the locking connection between the base and tube whereby the water is thrown in a series of streams by the pump against the walls of the pit.
13. In a pump of the character described, the combination of a pit, a tube projecting upwardly into the bottom of the pit, means for locking the pit and tube together, a head on the pit, a pump casing secured at its upper end to the head, the lower end of the casing being supported on the upper end of the tube which projects into the casing, and forming a water tight joint, a shaft mounted in the casing and suspended only from

the head, and an impeller secured to the lower end of the shaft, the pump casing and the projecting portion of the tube being spaced from the walls of the pit to form an annular passage adjacent and below the plane of the impeller.

14. In a pump of the class described, the combination of a pit, a head on the pit, a shaft suspended from the head, a casing 10 formed with outlet openings near the bottom and secured to the head and extending centrally within and spaced from the walls of the pit, an impeller secured to the lower end of the shaft and inclosed within the casing 15 adjacent the openings therein, and means in the bottom of the pit for supporting the weight of the casing and forming a water tight joint, the supporting means being below the plane of the impeller, and the casing 20 adjacent the impeller and below the plane of the latter being spaced from the walls of the pit.

15. In a pump, the combination of a cylindrical pit, a head on the pit, a cage supported in the pit having an annular series 25 of passages, spaced from the wall of the pit, the said passages being unobstructed so that the water may pass through the passages from the point at which it receives impulse 30 in unbroken tangential streams to the point of contact with the pit, an impeller mounted in the cage, a tubular casing extending up from the cage, a shaft mounted in the casing and secured to the impeller, means 35 for securing the casing to the head, bearings in the casing to support the shaft, and means for suspending the shaft from the head.

16. In a pump of the class described, the combination of a pit formed with an opening 40 and provided with a depending sleeve, a casing engaging the sleeve adjacent the opening, clamping means located in prox-

imity to the opening and adjustably securing the casing to the sleeve, said casing being supported at the bottom of the pit, a 45 shaft suspended from the head and fitting in the casing, and an impeller mounted on the shaft.

17. In a pump, the combination with a cylindrical pit, a head on the pit, an annular cage supported in the pit and including a series of spaced apart vanes, said vanes being tangent to the periphery of the cage and their ends being spaced from the walls of the cylindrical pit to form with the latter and the cage an annular unobstructed 50 passage, an impeller mounted in the cage, a tubular casing extending up from the cage, a shaft mounted in the casing and secured to the impeller, means for securing the 55 casing to the head, bearings in the casing to support the shaft, and means for suspending the shaft from the head.

18. In a pump, the combination with a cylindrical pit, a head on the pit, an annular cage supported in the pit and spaced from the wall thereof to form an unobstructed annular passage, said cage having a series of passages, each passage being tangent to the periphery of the cage and 60 unobstructed from end to end, an impeller mounted in the cage, a tubular casing extending up from the cage, a shaft mounted 65 in the casing and secured to the impeller, means for securing the casing to the head, 70 bearings in the casing to support the shaft, and means for suspending the shaft from the head.

In testimony whereof I affix my signature in presence of two witnesses.

FRED L. GETTY.
